UNITED STATES PATENT OFFICE.

FERDINAND PITSCHE, OF BERLIN, GERMANY, ASSIGNOR TO A. FRIES, HARDWARE WORKS, OF BERLIN, GERMANY.

SHOE-BUCKLE.

1,119,722.

Specification of Letters Patent.

Patented Dec. 1, 1914.

Application filed July 16, 1913. Serial No. 779,302.

To all whom it may concern:

Be it known that I, FERDINAND PITSCHE, working manager, a citizen of the Austro-Hungarian Empire, residing at Elisabeth 5 Ufer 50, in Berlin, in the Kingdom of Prussia and State of Germany, have invented a new and useful Improvement in Shoe-Buckles, of which the following is a specification.

10 The invention relates to shoe buckles and has for its object to provide a buckle, by which the buttoning or lacing of the shoe is rendered unnecessary and the shoe can be worn without pinching the foot of the 15 wearer.

A further object consists in applying means, which prevent a spontaneous releasing of the buckle, when locked.

The invention is illustrated in the annexed drawing, in which is—

Figure 1 a perspective view of a shoe provided with the new buckle, Fig. 2 a bottom plan view of the buckle and Fig. 3 a detail of the same buckle in a larger scale.

25 The improved buckle consists of a middle-piece *a* and two side-shanks *b*, *b*¹, which are attached to the piece *a* by a hinging connection, the shanks having on the corners of their inside edges lugs, locking into caps 30 *c*, *c*¹ formed on the middle-piece. The opposite connecting edges *d* of this piece are provided with cuttings, such forming springs *e*, *e*¹, while the inside corresponding edges of the shanks have projections *f* bent 35 downwardly, which in the locked position of the buckle are engaged by the said springs and pressing in this manner the side-shanks against the middle-piece prevent the spontaneous releasing of the locking. The outer 40 edges of the shanks are attached to the shoe

g by yielding means as elastics *h*, *h*¹. The middle piece *a* may be cut from a plate or bent from a wire, in which case it is provided with an ornamental plate for covering the elastics *h*, *h*¹, when the buckle is locked. 45

As shown in Figs. 2 and 3 the lugs on the corners of the side shanks acting as hinge tenons are provided with spiral springs *i*, *i*¹. Hereby the locking of the buckle is obtained at any time automatically, as the spiral 50 springs force the shanks *b*, *b*¹ to take the inward position. In opening the buckle the middle-piece *a* will be seized by the fingers of the wearer and drawn up, whereupon the side-shanks will be turned on their hinges 55 and released from the engagement with the springs *e*, *e*¹. It will also be understood, that the yielding connections *h*, *h*¹ of the buckle with the shoe *g* will prevent the pinching the foot of the wearer. 60

Having thus fully shown and described my invention, what I claim as new and desire to secure by Letters Patent, is:—

In a shoe-buckle the combination of a middle piece, two side shanks attached on 65 their inner edges to the middle piece by a hinging connection and on their outer edges to the shoe by a yielding connection, the connecting edges of the middle piece having cuttings forming springs and the corresponding edges of the shanks projections bent downwardly and spiral springs arranged on the hinge-tenons for the purpose set forth. 70

In testimony whereof, I affix my signature 75 in presence of two witnesses.

FERDINAND PITSCHE.
